J. D. ELLIS

NUT LOCK

Filed Jan. 20, 1922

FIG. 1.

FIG. 2.

FIG. 3.

FIG. 4.

Inventor
J. D. Ellis.

By
Ralph J.
Ellis, Attorney

UNITED STATES PATENT OFFICE.

JULIUS D. ELLIS, OF FULTON, NEW YORK.

NUT LOCK.

Application filed January 20, 1922. Serial No. 530,626.

To all whom it may concern:

Be it known that I, JULIUS D. ELLIS, a citizen of the United States, residing at Fulton, in the county of Oswego and State of New York, have invented certain new and useful Improvements in Nut Locks; and I do hereby declare the following to be full, clear, and exact description of the invention, such as will enable others skilled in the art 10 to which it appertains to make and use the same.

The invention has relation to lock means, and more particularly to devices for securing nuts and burrs upon bolts, or like parts, 15 to prevent their loosening and displacement when subjected to vibration or other causes tending to effect backward rotation of a nut upon the bolt or like part upon which it is threaded.

20 The invention provides lock means which, when applied to a nut, will not interfere with the free and ready application of a wrench or like tool generally employed for rotating the nut to effect a tightening thereof, said 25 lock means being readily operable without requiring the application of any tool or instrument and which has indicated means associated therewith so that it may be ascertained when the nut is locked or released, 30 whereby the nut may be used repeatedly without impairment of the efficiency of the lock means.

Other objects and advantages will be apparent and suggest themselves as the nature 35 of the invention is understood.

While the drawings illustrate an embodiment of the invention, it is to be understood that in adapting the same to meet different conditions and requirements, various changes 40 in the form, proportion and minor details of construction may be resorted to without departing from the nature of the invention.

Referring to the accompanying drawings forming a part of the application,

45 Figure 1 is a perspective view of a nut provided with locking means embodying the invention,

Figure 2 is an elevation partly in section, showing the nut applied to a bolt,

50 Figure 3 is a sectional view taken on the plane indicated by the line 3—3 of Figure 2.

Figure 4 is a detail perspective view of the rocker and lock bolt.

Corresponding and like parts are referred 55 to in the following description and design-

nated in the several views of the drawings by like reference characters.

The numeral 1 designates a nut or burr which may be of any approved construction and which is provided with the usual threaded opening or eye 2 for the reception of a bolt 3 or like part. A channel 4 is provided in an edge of the nut 1 and receives a slide 5 which snugly fits the same. A recess 6 is formed in the edge portion of the nut 1 provided with the channel 4 and is in communication with the latter and adapted to be closed by means of the slide 5. The recess 6 is widened at one end, as indicated at 7. An opening 8 leads from the widened portion 7 of the recess and extends into the opening or eye 2 of the nut.

A rocker 9 snugly fits the recess 6 and is provided in its upper edge with a notch 10 which receives a pin 11 carried by the slide 5. 75 Longitudinal movement of the slide 5 effects a rocking of the part 9. A lock bolt 12, fitted in the opening 8, is provided at its upper end with a hook 13 which engages a notch 14 in the end of the rocker 9 adjacent the opening 8. The widened portion 7 of the recess 6 accommodates the hook end 13 of the lock bolt 12 and the inner end of the latter is projected into the opening 2, or withdrawn therefrom by a rocking of the part 9 when 85 sliding the part 5.

The bolt 3, or like part, is provided with one or more longitudinal grooves 15 in its threaded portion to receive the inner end of the lock bolt 12, whereby to secure the 90 nut 1 and hold the same in the required adjusted position. Movement of the slide 5 in one direction results in projecting the lock bolt 12 into positive engagement with the bolt 3 or like part and movement of 95 the slide 5 in an opposite direction withdraws the lock bolt 12 from engagement with the part 3, whereby the nut 1 is released and may be removed and used again since the locking means have not suffered 100 any injury or impairment in the removal of the nut which is adapted for repeated use.

Indicating means are provided whereby it may be readily ascertained when the lock 105 bolt is in engagement with the bolt 3 or released therefrom. The indicating means consist of a mark 16 on the slide 5 and corresponding marks on an edge portion of the nut 1 at one side of the channel 4 110

and designated by the letters O and S. When the slide 5 is moved to bring the mark 16 thereof in register with the mark designated by the letter O, it indicates that 5 the lock is off, and when the slide 5 is moved to bring the mark 16 in line with the mark designated by the letter S, it indicates that the lock bolt is shut or projected into engagement with the part 3, whereby the nut 10 1 is made secure and safe against casual displacement.

What is claimed is:

1. A nut lock comprising a lock bolt, a rocker associated with said lock bolt, a 15 slide, and means forming a connection between said rocker and said slide, and the parts being so disposed that rectilinear movement of the slide effects longitudinal movement of the lock bolt to secure or release the nut as required.
2. A nut having a recess in an edge portion and an opening leading from an end of the recess into the threaded eye, a lock bolt disposed in said opening, a rocker arranged in the recess and having an end portion in engagement with the lock bolt, and a slide closing the recess and adapted to operate the rocker and lock bolt.
3. A nut having a recess in an edge portion, an opening leading from an end of the recess into the threaded eye of the nut and having a channel in the recessed edge, a lock bolt mounted in said opening, a rocker in the recess and having an end in engagement with the lock bolt, and a slide mounted in the channel and closing the recess and having a portion in engagement with the rocker to effect positive movement of the lock bolt in each direction.
- 40 4. In combination, a nut having a chan-

nel, a recess and an opening in an edge portion, the recess being widened at one end and the widened portion of the recess being in line with said opening, a rocker disposed in the recess and having a notch 45 in its outer edge and a notch in the end adjacent the widened portion of the recess, a lock bolt in said opening having a hook at its outer end engaging the notch in the end of the rocker, a slide fitting said channel and closing said recess, and a pin projecting from the slide and entering the notch in the outer edge of the rocker, the parts being so disposed whereby longitudinal movement of the slide actuates the lock 50 bolt through the instrumentality of the rocker.

5. In combination, a nut, a lock bolt slidably mounted in said nut and adapted to be projected through the periphery of the 60 screw threaded opening therein, a slidable member on said nut, and means connecting said slidable member to said lock bolt, whereby when said member is moved in one direction the bolt will be retracted and when the member is moved in the opposite direction the bolt will be projected.

6. In combination with a nut, a lock bolt, means slidable to project or retract said lock bolt, said means concealing said lock 70 bolt, and means cooperating with said means to indicate the relative position of said lock bolt.

In testimony whereof I affix my signature in presence of two witnesses.

JULIUS D. ELLIS.
